AUTOMATIC GAIN CONTROL

Paul Borias, Paris, France, assignor to Compagnie Generale de Telegraphie Sans Fil, a corporation of France

Application June 27, 1930, Serial No. 464,195
In France June 29, 1929

1 Claim. (Cl. 250—20)

The present invention relates to improvements in amplifiers of oscillatory currents, for example those used in radio telegraphic and radio telephonic reception.

5 One of the main objects of the invention is to provide automatic regulation of the sensitivity of a receiver so as to maintain the intensity of reception at an appreciably constant level, in spite of variations of the energy received, for example 10 an anti-fading device.

Another object of the invention is to provide 15 decrease in the reception intensity to any suitable desired value, i. e., a device for the control of the sound volume.

15 Another important object of the invention is to provide a receiver wherein these two effects are easily, and advantageously, combined by the action of cooperating elements when being produced.

20 Briefly, the construction upon which the invention is based, involves the combination of an indirectly heated tube, used as detector tube, with a resistance which is to produce a variable ohmic drop, the resistance being interposed between the emitting cathode and the negative pole of the plate potential source. The other means according to the invention, combined with the preceding ones, consists of amplifying elements with electronic emission elements, preceding the detector, 25 the control electrodes of the elements being controlled in potential by the potential drop in the above mentioned resistance, and of devices for adjusting the feed potential of the amplifying elements at will to a convenient and variable 30 value.

35 The novel features which I believe to be characteristic of my invention are set forth in particularity in the appended claim, the invention itself, however, as to both its organization and 40 method of operation will best be understood by reference to the following description taken in connection with the drawing in which I have indicated diagrammatically several circuit organizations whereby my invention may be carried into 45 effect.

In the drawing,

Fig. 1 diagrammatically shows an amplifying detecting device whose sensitiveness is automatically controlled in accordance with the invention, 50 Fig. 2 shows a device of the preceding type, means being added, in accordance with the invention, for the regulation of the feed potential of the electrodes of the amplifier which means may be utilized, if need be, as elements for the 55 volume control.

Referring to the accompanying drawing in which like characters of reference indicate the same parts in the different figures, an anti-fading receiver is shown in Fig. 1, the latter disclosing detection of the radio frequency oscillations by means of a multi-electrode tube 1, termed an "indirectly heated" tube, i. e. provided with a cathode 2 heated indirectly by a heating element 3. The anode 4 of this tube is supplied by a source of direct current potential B, the positive terminal of the source being connected, by means of any suitable coupling device 5, with the utilization circuit 6, the latter being subsequent amplification stages or even a reproducer.

For the sake of simplicity, the connections of 15 the control electrode 7 of detector tube 1 are not shown and they may be established in any of the manners known in the prior art.

The emitting cathode 2 is connected to the negative terminal of the anode source B across 20 a resistance 8, the latter being preferably shunted by a capacity 9. One, or more, amplifying tubes 10, 11 are connected preceding detector 1, and are operated in such a manner that the polarization potential of their control electrodes 25 is derived from the potential at the terminals of resistance 8.

Assuming, for example, that the cathodes of tubes 10 and 11 (which may be heated directly) are connected to the negative terminal of source 30 B and, accordingly, to one of the terminals of resistance 8, the return circuit of their control electrodes to the cathode will be joined to the other end of resistance 8, as seen in Fig. 1. An adjustable source 12, for the adjustment of the 35 feed potential, may optionally be inserted in this circuit. There are not shown, also for the sake of simplicity in order to facilitate the understanding of the invention, with respect to these tubes, the heating circuit of their filament, nor the input 40 circuits or elements of the control electrode, nor their output circuits, or anode circuits, all of which may be effected and arranged in any well known manner.

According to Fig. 2, the circuit arrangement 45 of the type shown in Fig. 1 is modified so that the amplifier tubes 10 and 11 have their grid potentials fixed by the connection of point 13, of their common filament heating circuit, to the slideable contact of a potentiometer resistance 14 50 shunting the anode source B. This arrangement is completed by the addition of a condenser 15 between the connecting wire 13, 14 and the negative terminal of the anode source. This circuit furnishes means, by the manipulation of the con- 55

tact of potentiometer 14, for adjusting the potential of rest of the grids of tubes 10 and of 11, at will, to the suitable negative value with respect to the cathodes of the same tubes. It is 5 a matter of course that the heating circuit of the said cathodes must, on the other hand, be insulated.

In Fig. 2 are indicated the connecting arrangements of the input and output circuits of tubes 10, 11, 1, the input circuit of tube 16, the heating circuit of tube 1. Thus, tubes 10, 11 and 1 are excited by means of tuned radio frequency transformers T, T', T'', and tube 16 by means of an audio frequency transformer T''', the primary 15 of the latter being shunted by capacity 17. The assembly of the device is particularly well adapted to the construction of a receiver operating with frequency change, the tubes 10 and 11 acting the part of amplifiers of currents of medium frequency, tube 1 the one of second detector and tube 16, and possible following ones, that of amplifiers for low frequency currents.

It is not thought necessary to show the details of the connections of these latter tubes nor 25 of those of preceding tube 10. It should be noted that the described arrangements furnish anti-fading amplifiers-detectors which may be fed entirely by the domestic light circuit, disposing of any use of batteries, equalization batteries or 30 accumulators and thereby represent new industrial products. To this end, the heating circuit of tubes 10 and 11 is fed by the secondary A of a transformer whose primary is branched off the supply line, the latter not being shown. Another secondary A' grounded at M, feeds the heating circuit of detector 1 and, as the case may be, 35 of other tubes.

The operation of both Figs. 1 and 2 will now 40 be described. In both Figs. 1 and 2 the detector is of the grid leak type (as shown specifically in Fig. 2 at 9') and therefore has a decreased anode current flow when the signal input increases. Hence, the drop across resistor 8, in 45 each figure, decreases when the signal input to the detector 1 rises above the desired volume level. In Fig. 1, the battery 12 is employed for maintaining the grids of tubes 10, 11 negative with respect to the cathodes thereof. It is to be understood that between terminals a and a', and b, b', are connected the tuned input circuits 50 of the amplifier stages, as shown in detail in Fig. 2.

It will now be seen that a rise of signal input to detector 1 above a desired volume level 55 results in a drop in anode current flow across resistor 8. The point c of resistor 8 becomes less positive, and this results in the grids of tubes 10, 11 becoming more negative with respect to the cathodes thereof. The radio frequency amplification thereupon becomes less, and the signal input to detector 1 decreases to the desired

level. The reverse action takes place for signal inputs to the detector below the desired volume level. Of course, at the desired volume level there exists at the grids of tubes 10, 11 a predetermined positive potential from point c in opposition to the negative potential derived from source 12. 5

In Fig. 2, slider 14' determines the potential of the cathodes of tubes 10, 11 with respect to the grids thereof. This is so since the grids of tubes 10, 11 are connected through lead 10', resistor 8, and lead 11' to the ground side of resistor 14. Hence, slider 14' (operating through lead 20) functions as a manual volume control by adjusting the cathode potential of each of tubes 10, 11. The resistor 8 functions, as in Fig. 15 1, as a compensating resistor, and when the signal input to detector 1 rises above the desired volume level, the detector anode current drops.

There results a decreased drop across resistor 20 8, the point c becomes less positive, and the grids of tubes 10, 11 become less positively biased (or more negative therefore) with respect to the cathodes thereof. The action is the same as described in connection with Fig. 1, and need not be repeated. 25

Finally, the anode source B will be established by means of one of the usual rectifying connections. It may prove of advantage to make use of a single transformer with multiple secondaries for supplying the entire apparatus including the 30 rectifier. Also that while I have indicated and described several systems for carrying my invention into effect, it will be apparent to one skilled in the art that my invention is by no means limited to the particular organizations 35 shown and described, but that many modifications in the circuit arrangements, as well as in the apparatus employed, may be made without departing from the scope of my invention as set forth in the appended claim. 40

What I claim is:

In a radio receiver, a radio frequency amplifier including an electron discharge tube, a detector of the grid leak type comprising an electron discharge tube provided with an electron emission electrode and a heating filament for said electrode, a source of potential for the anode of said detector tube, an impedance connected at one terminal thereof to the said emission electrode and the input circuit of said amplifier tube, the opposite terminal being connected to the negative side of said source, a second impedance connected between the terminals of said potential source, said one terminal being connected to the signal input grid of the 55 amplifier tube, and manual volume control means connected between a point on the second impedance and the amplifier cathode in said amplifier input circuit.

PAUL BORIAS. 60
